UNITED STATES PATENT OFFICE.

HARRY R. DENIS, OF NEW ORLEANS, LOUISIANA, AND CHARLES BRAMBERG, OF BROOKLYN, NEW YORK, ASSIGNEES TO HENRY DENIS, OF NEW ORLEANS, LOUISIANA.

METALLIC ENVELOP-SEAL.

SPECIFICATION forming part of Letters Patent No. 564,781, dated July 28, 1896.

Application filed October 4, 1895. Serial No. 564,619. (No model.)

To all whom it may concern:

Be it known that we, HARRY R. DENIS, of New Orleans, Louisiana, and CHARLES BRAMBERG, of Brooklyn, New York, have invented 5 new and useful Improvements in Metallic Envelope-Seals, which are fully set forth in the following specification.

The object of this invention is to furnish means for securely fastening envelopes, so that 10 they cannot be opened and their contents tampered with without cutting the paper or mutilating the seal. The essentials of such a device are that it should be very cheap and easy to make, so as not to add materially to 15 the cost of the envelop; that it should be small and easy of application, requiring no tools or implements on the part of the user, and above all that it should offer absolute security against tampering. It has been found 20 exceedingly difficult to combine all these requisite properties in one structure, but the device herein described is believed to fulfil all the desired conditions.

Heretofore an envelop-seal has been de- 25 vised consisting of two disks, one fastened to the body and the other to the flap of the envelop. The latter element carried a bulbous stud which was designed to be forced into and permanently held by an aperture in the 30 other disk, the latter being of spring-metal, so as to clasp the neck of the stud. While this device measurably fulfilled the objects in view, it has been found possible by care and ingenuity to pry the stud out of its clasp 35 without mutilating the seal or envelop. This is possible with two disks lying one on the other, presenting two metal pieces between which an instrument can be inserted to force the elements apart.

According to the present invention the relatively-movable element, attached to the flap of the envelop, is fastened to the stationary element by being thrust into a thin space formed between two plates of the latter. The 40 tongue on the movable or male element has a hook, shoulder, or projection which, when the tongue is fully inserted, is caught by a spring plate or catch concealed and rendered inaccessible by the top plate of the station- 45 ary element. This part of the device is sus-

ceptible of considerable modification, but it will be shown herein in the simplest form in which we have contemplated applying it. The two parts obviously cannot be forced apart without completely rupturing the seal, 55 and as the engaging devices, by which the parts are connected, are absolutely inaccessible, the objects of the invention are effectually secured. The tongue is preferably secured to the flap by means of an eyelet as 60 commonly used in paper-fasteners; but if it be desired to sell the seals separately from the envelopes and to render the use of a die unnecessary for attaching them to the envelop this element may be provided with 65 flexible metallic prongs, as heretofore. The latter plan will serve well for envelopes used in ordinary correspondence. The former is preferred for envelopes containing valuable papers, where the utmost security is desired. 70

In the accompanying drawings, which form part of this specification, Figure 1 represents the seal applied to an envelop. Fig. 2 is a longitudinal section on an enlarged scale. Fig. 3 is a rear view showing the two parts 75 connected. Fig. 4 is a similar view showing the parts disconnected. Fig. 5 is an edge view, and Fig. 6 an end view, of the stationary element.

The male element of the seal consists of 80 the tongue *a*, projecting from the eyelet *b*. The latter is provided with the flange *b'*, Fig. 5, which is upset in the usual way when the device is attached to the flap *A* of an envelop. The tongue *a* has at its end a hook, projec- 85 tion, or shoulder *a'*. The other element, which is attached to the body *B* of the envelop, is composed of an upper plate *c* and a lower plate *d*, between which is formed a pocket *c'*, having its entrance at the side of 90 the element. This pocket should preferably correspond in shape with the tongue *a* and be of such size that the latter will fill it, leaving no room for the insertion of any instrument. 95

The lower plate *d* is partly cut away, as at *e*, and a lip *d'* is formed by two parallel cuts. This lip constitutes a spring catch or detent for engagement with the hook *a'*, and being of metal is slightly resilient. 100

Plate c^2 is formed at c^2 with an incline or cam surface. As the tongue a is inserted in the pocket its end encounters this surface, forcing it downward, projection or hook a' depressing spring-lip d' until the former reaches the end of the lip, when the latter springs back to its normal position, locking the tongue in place. From examination of Fig. 1 it will be seen that this attachment is permanent, and that the envelop can only be opened either by breaking the seal or tearing the paper. In the form shown in the drawings the prongs f , by which this element of the seal is attached to the envelop, are in one piece with the upper disk c . Consequently the two disks cannot be pried apart or separated without tearing the paper.

Details of construction may obviously be varied, the device as described and as shown in the drawings being exhibited to illustrate the simplest and most efficient manner now known to us of applying the principle of the invention.

Having thus particularly described our invention, what we claim as new, and desire to secure by Letters Patent, is—

1. The combination with the tongue having means for attaching it to the flap of an envelop, and provided with a hook, of a complementary device having means for attachment to the body of an envelop, and provided with a laterally-open pocket, the dimensions of said pocket being such that the tongue when inserted will fill it and in which is a concealed spring-catch for engaging and locking the hook on said tongue, substantially as described.

2. The combination with the tongue having on one end a hook and on the other means for attaching it to an envelop, of a complementary element composed of two plates,

forming between them a pocket opening laterally, the concealed plate being provided with a spring lip or catch for engagement of said hook, substantially as described.

3. The combination with the tongue having a hook on its end, of the complementary element composed of two plates forming between them a pocket, the concealed plate being cut as specified to form a lip or catch, and the outer plate being provided with an inclined surface at the end of the pocket, substantially as and for the purpose set forth.

4. The combination with the tongue provided with a hook or projection, of the complementary element composed of two plates forming between them a pocket and provided with a catch in said pocket for engaging said hook or projection, the outer plate having integrally-formed fastening devices for securing the element to an envelop, substantially as described.

5. An envelop-fastener comprising a tongue having means for fastening it to the envelop, said tongue being provided on its end with a hook, a complementary element comprising two disks or plates fastened together and forming between them a pocket in which the tongue closely fits, the concealed plate being provided with a spring portion which yields to admit the hook and springs back to catch it, and the outer plate having an inclined surface at the end of the pocket, substantially as described.

In testimony whereof we have signed this specification in the presence of two subscribing witnesses.

HARRY R. DENIS.
CHARLES BRAMBERG.
